DESIGN FOR A RADIO CABINET OR SIMILAR ARTICLE

John F. Radebaugh, Springfield, Mass.

Application June 20, 1946, Serial No. 130,873

Term of patent 14 years

(Cl. D56—4)

To all whom it may concern:

Be it known that I, John F. Radebaugh, a citizen of the United States, residing at Springfield, in the county of Hampden and Commonwealth of Massachusetts, have invented a new, original, and ornamental Design for a Radio Cabinet or Similar Article, of which the following is a specification, reference being had to the accompanying drawings, forming part thereof.

Fig. 1 is a perspective view of a radio cabinet showing my new design;

Fig. 2 is a front elevational view of the radio cabinet shown in Fig. 1; and

Fig. 3 is a plan view of the radio cabinet shown in Figs. 1 and 2.

I claim:

The ornamental design for a radio cabinet or similar article, as shown.

JOHN F. RADEBAUGH.
